UNITED STATES PATENT OFFICE.

ANKER PETERSEN, OF BOSTON, MASSACHUSETTS, ASSIGNOR TO BOSTON MACHINERY COMPANY, OF BOSTON, MASSACHUSETTS, A CORPORATION OF MASSACHUSETTS.

BRAIDING-MACHINE.

1,305,490.

Specification of Letters Patent. Patented June 3, 1919.

Application filed July 7, 1916. Serial No. 108,070.

To all whom it may concern:

Be it known that I, ANKER PETERSEN, a citizen of the United States, and resident of Boston, in the county of Suffolk and State 5 of Massachusetts, have invented new and useful Improvements in Braiding-Machines, of which the following is a specification.

This invention relates to rotary braiding machines, and particularly to braiding machines of the type having a main revolving frame within which a series of thread carriers are revolved in the opposite direction by a revolving roller frame, the main revolving frame carrying strand guides for 10 passing the strands over and under said thread carriers. The invention consists in the novel features of construction herein-after described and particularly pointed out in the claims.

20 In the accompanying drawings which illustrate one embodiment of the invention, and show such parts only of the braiding machine as a whole as are necessary for an understanding of the novel features of the 25 invention,—

Figure 1 is a vertical section of a part of a braiding machine containing the invention;

Fig. 2 is a fragmentary view, partly in 30 plan and partly in horizontal section, of a pair of rollers and friction wheels carried by the revolving roller frame; and

Fig. 3 is an end view of one of said rollers and the friction wheel secured thereto.

35 Referring to the drawings, 1 represents the frame of the machine, preferably made spider shaped, and provided with a central hub 2 which supports a central tubular shaft 3, at the top of which the fabric is formed. 40 The shaft 3 is surrounded by a sleeve 4 which is rotatable on shaft 3 and has secured to it, by means of a set screw 6, a bevel gear 5 which rotates on the upper face of hub 2. The braided fabric passes down 45 through the hollow shaft 3 to a takeup mechanism of usual construction (not shown). A driving shaft 7 journaled in bracket 8, carried by the main frame, is provided at its inner end with a pinion 10

which meshes with and drives the bevel gear 5.

Upon the sleeve 4 above the bevel gear 5 is a revolving frame 11 which supports the strand guides (not shown) in the usual way, and is revolvable on sleeve 4. The frame 11, 55 which may be termed the main revolving frame, is provided with a bevel gear 12 on its under side engaging the pinion 10. Thus the frame 11 and the parts carried thereby are caused to revolve in opposite directions 60 to the sleeve 4 and the parts carried thereby.

Above the frame 11 is a disk 13 fast on sleeve 4 and turning therewith, to which are secured concentric annular rims 14 and 15 connected by radial arms 16, the inner rim 65 14 being mounted on the disk 13. The disk 13 with its rim and radial arms may be termed the roller frame. In each of the segmental spaces between the rims 14 and 15 and the arms 16, there is journaled a 70 pair of rollers for supporting and driving the thread carriers herein-after described, each roller comprising an outer roller element 17 and an inner roller element 18 connected by a shaft 19 disposed radially of 75 the roller frame and journaled at its ends in the rims 14 and 15.

A friction wheel 20 made of felt or other suitable compressible resilient material, is fixed to the outer side of each roller 17 so 80 that it rotates therewith. Preferably said friction wheel is in the form of an annulus secured to the outer face of the roller 17 by means of a washer or ring 21 secured to the roller 17 by screws 22. Said annular friction wheel 20 and said washer wheel 21, as herein shown, are fitted over the outside of a flange or rim 17^a on the roller 17. Thus the friction wheels are readily removable and replaceable in case they become worn 90 or damaged. A ledge or flange 23 is secured to the inner side of the upright portion 24 of the main revolving frame 11, and the friction wheels 20 run on said ledge 23 thereby rotating the supporting and driving 95 rollers 17—18.

A series of thread carriers 25, each adapted to carry a cop or mass of thread, are

mounted in the several segmental spaces between the rims 14 and 15 and arms 16, each being supported and driven by one of the pairs of rollers on the roller frame. At the 5 inner end of each thread carrier 25 is a roller 26 resting on a pair of rollers 18, and at the outer end of each thread carrier is a roller 27 resting on the corresponding pair of outer rollers 17. Said thread carriers 10 may also have horizontally disposed rollers 28 which run in guideways 29 on the main revolving frame to take up the centrifugal thrust as the said carriers revolve about the machine. Each thread carrier may also 15 have a roller 30 at the top, aiding in resisting centrifugal thrust, and coöperating with guard ring 31 to prevent the thread carrier from being dislodged inwardly from its position.

20 As the main revolving frame and the roller frame are revolved in opposite directions about the machine, and the thread or strand T is carried over and under the thread carriers in the usual manner, the passage of the thread T between the thread carrier rollers and the supporting and driving rollers is aided by the rotation of the said rollers by means of the friction wheels traveling on the ledge 23 on the main revolving frame. The relatively positive drive of said 25 rollers caused by said friction wheel is of especial advantage where the machine is operated upon light material which would be likely to break if the rollers were idler rollers and the tension of the thread itself 30 were relied upon to pull the thread between the rollers.

I claim:

1. A braiding machine comprising a fixed 40 and a main revolving frame, a revolving roller frame, means to drive said frames in opposite directions, thread-carrier supporting and driving rollers arranged in pairs on radially disposed axes carried by said 45 roller frame, a series of thread carriers each having a roller resting on one of said pairs of supporting and driving rollers, and friction wheels fixed to said supporting and driving rollers to turn therewith and coöperating with said main revolving frame to 50 rotate said supporting and driving rollers and also said rollers on the thread carriers.

2. A braiding machine comprising a fixed and a main revolving frame, a revolving 55 roller frame, means to drive said frames in opposite directions, thread carriers, supporting and driving rollers arranged in pairs on radially disposed axes carried by said roller frame, a series of thread carriers 60 each having a roller resting on one of said pairs of supporting and driving rollers, and friction wheels fixed to said supporting and driving rollers to turn therewith, and a

ledge on said main revolving frame on which said friction wheels run, thereby rotating said supporting and driving rollers and also said rollers on the thread carriers. 65

3. A braiding machine comprising a main revolving frame, a revolving roller frame, means to drive said frames in opposite directions, supporting and driving rollers each comprising an inner and outer roller element connected by a shaft, said rollers being arranged in pairs on radially disposed axes carried by said roller frame, a series of 70 thread carriers each having a roller at its outer end and a roller at its inner end resting respectively on the outer roller elements and the inner roller elements of one of said pairs of supporting and driving rollers, 75 roller bearing means for the thread carriers for preventing centrifugal displacement on said supporting and driving means and friction wheels fixed to said supporting and driving rollers to turn therewith and coöperating with said main revolving frame to 80 rotate said supporting and driving rollers and also said rollers on both ends of the thread carriers.

4. A braiding machine comprising a main 85 revolving frame, a revolving roller frame, means to drive said frames in opposite directions, supporting and driving rollers each comprising an inner and outer roller element connected by a shaft, said rollers being 90 arranged in pairs on radially disposed axes carried by said roller frame, a series of 95 thread carriers each having a roller at its outer end and a roller at its inner end resting respectively on the outer roller elements 100 and the inner roller elements of one of said pairs of supporting and driving rollers, and friction wheels fixed to said supporting and driving rollers to turn therewith, and a ledge on said main revolving frame on 105 which said friction wheels run, thereby rotating said supporting and driving rollers and also said rollers on the thread carriers.

5. A braiding machine comprising a main 110 revolving frame, a revolving roller frame, means to drive said frames in opposite directions, supporting and driving rollers arranged in pairs on radially disposed axes carried by said roller frame, a series of 115 thread carriers each having a roller resting on one of said pairs of supporting and driving rollers, and friction wheels of compressible resilient material fixed to said supporting and driving rollers to turn therewith and coöperating with said main revolving frame to 120 rotate said supporting and driving rollers and also said rollers on the thread carriers.

6. In a braiding machine, a thread carrier supporting and driving roller, having 125 removably fixed to one side thereof an an-

nular friction wheel of greater diameter than said roller of compressible resilient material.

7. A braiding machine having a thread carrier, supporting and driving roller having attached thereto to rotate therewith an annular friction wheel lying at one side of said roller, in combination with bearing

means on the carrier bearing on said roller and means for preventing said bearing 10 means from being displaced centrifugally against said friction wheel.

Signed by me at Boston, Massachusetts, this 27th day of June 1916.

ANKER PETERSEN.
